UNITED STATES PATENT OFFICE.

MARTIN J. O'BOYLE, OF CLEVELAND, AND EDWARD C. HOLTON, OF OLMSTED FALLS, OHIO, ASSIGNORS TO THE SHERWIN WILLIAMS COMPANY, OF CLEVELAND, OHIO, A CORPORATION OF OHIO.

METHOD OF AND APPARATUS FOR EVAPORATING LIQUIDS.

Application filed April 12, 1918. Serial No. 228,166.

To all whom it may concern:

Be it known that we, MARTIN J. O'BOYLE and EDWARD C. HOLTON, both citizens of the United States, and residents of Cleveland, county of Cuyahoga, and State of Ohio, and of Olmsted Falls, county of Cuyahoga, and State of Ohio, respectively, have jointly invented a new and useful Improvement in Methods of and Apparatus for Evaporating Liquids, of which the following is a specification, the principle of the invention being herein explained and the best mode in which we have contemplated applying that principle, so as to distinguish it from other inventions.

The present invention, relating, as indicated, to methods and apparatus for drying materials held in solution or suspension in a liquid, is more particularly directed to a method and apparatus for preventing loss of time caused by shutting down the apparatus to remove deposits formed at various points in the apparatus. It has been found in such methods, and in the usual apparatus used for carrying out such methods, that considerable difficulty is met with from the carrying over into the exhaust conduits of some of the material in the drier. Any material so carried over deposits at some point in the discharge conduits and blocks these so that the apparatus must be opened frequently for cleaning, causing a very material reduction in the available operating time of the apparatus. Material has also been found to deposit at other points, which will be hereinafter pointed out, with great detriment to continuous and efficient operation. It is one object of the present invention to avoid these difficulties by the methods and the apparatus which will be hereinafter described. To the accomplishment of the foregoing and related ends, said invention, then, consists of the means hereinafter fully described and particularly pointed out in the claims.

The annexed drawings and the following description set forth in detail certain means and one mode of carrying out the invention, such disclosed means and mode illustrating, however but one of various ways in which the principle of the invention may be used.

In said annexed drawings:

Fig. 1 is a side elevation, partially in transverse section, through a drier, shown

more or less diagrammatically, in which is embodied one form of our improved apparatus: Fig. 2 is a side elevation of the drying cylinder with one form of our improved apparatus embodied therein; and Fig. 3 is an enlarged partial section on the same plane as Fig. 1.

There are of course various types of drying apparatus in general use for carrying out the same general process of drying evaporated liquids and separating therefrom materials held in solution or suspension. The accompanying drawings show in a diagrammatic way only one typical drier, to which our improved apparatus has been attached, but it is understood, and it will be evident from the following description, that our improvements are capable of incorporation in various types of apparatus for this general purpose.

In Fig. 1 there is shown a casing 1 of general cylindrical form, but provided with an enlarged body portion 2, in which there may be suspended or constructed a liquid-receiving tank 3 for holding the liquid and material which is to be transferred to the circumference of a rotary cylinder or drying member 4. This latter member is a plane smooth cylinder closed at either end and heated internally by any suitable means, usually by means of steam introduced at one end and discharged at the other through trunnion bearings. This cylinder is rotated at a relatively low speed and at its bottom dips into the surface of the liquid held in the tank 3, although in some forms of driers this liquid is sprayed against the surface of the drum at this same point in its revolution. The cylinder is rotated in the direction of the arrow shown in Fig. 1 and on the lower left-hand side of the cylinder are disposed scraping members in the form of knives 5 which contact against the surface of the cylinder and scrape therefrom the material which has been dried during the revolution of the cylinder. This material as it is removed from the drying cylinder falls into a conduit 6 in the left-hand side of the base in the chamber 1, and is removed therefrom by any suitable conveying means, such, for example, as the screw conveyor 7 shown.

Any suitable means may be employed for maintaining liquid in the tank 3 and we have shown a pump 8 con-

23
nected to the reservoir 9 in the base of the chamber 1 for this purpose.

During the operation of the cylinder a high vacuum is maintained in the chamber 1, this chamber being connected by means of a goose-neck conduit 10 with a dust filter 11, which is in turn connected to a separating cylinder 12, which opens at its bottom into a stand pipe 13. The stand pipe 13 is connected to a suitable water connection, such as a sewer or well 14, while the upper end of the separating chamber 12 is connected to a vacuum pump 15 by means of a conduit 16. As to the operation of the vacuum system it is sufficient to say that the vacuum is maintained in the drum by the suction through the goose-neck 10, the dust filter 11 and the separating chamber 12, which latter means allows any vapor, such as water vapor, in the air drawn from the chamber 1 to be condensed and to flow down into the stand pipe 13, while the air and other gases, if any, are carried through the conduit 16 and discharged from the vacuum pump 15.

To operate efficiently, an apparatus, such as is diagrammatically shown in the drawings and briefly explained above, should operate to cause no deposit at any point in the system, except possibly in the dust filter 11, which is built into the system for removing any dust or other solid material which may by chance be carried over with the evaporated liquid from the chamber 1. If, however, the suction action has slowed up at any point, the movement of air and vapor through the goose neck 10 will be correspondingly lessened and any solid material carried in suspension by the air and vapor, will tend to deposit at this point, and after a relatively short time will block this passage to such an extent that the operation of the apparatus must be stopped and the goose neck and other parts opened for cleaning. This blocking of the goose-neck conduit 10 may occur within a few hours and necessitates the shutting down of the entire apparatus for cleaning with a consequent considerable loss in time and output.

50 We have found that the above defects in the apparatus may be entirely remedied by opposing to the discharging vapor and suspended material a curtain or sheet of some vapor such as steam, which will entrain any suspended material from the discharging vapors and carry it to the sides of the conduit 10, and from the walls of this conduit back into the cylinder 1 or into the dust filter 11. We provide this curtain or sheet of vapor by interposing a steam pipe 17 in the goose neck 10, the pipe being curved somewhat to conform to the curvature of the goose neck and extending from the point of connection of the goose neck and the chamber 1 to a point somewhat beyond the

central vertical plane through the goose neck. This steam pipe 17 is provided with a series of apertures 18 throughout its length, its ends being closed and a series of jets of steam are thus discharged radially in all directions from the center toward the walls of the conduit 10, in this way opposing a curtain of steam of considerable length to the passage of any particles of solid matter through this conduit. All of the particles of solid matter which are carried by the discharge vapor are brought to the walls of the conduit 10 by the action of these jets of steam, and it is immaterial whether the collected matter then falls into the dust filter 19 or back into the liquid reservoir in the chamber 1.

Another defect in the operation of drying apparatus of this general type is that the knives 5 cannot be made to hug the surface of the cylinder closely enough to prevent the passage of some material between the knife and the cylinder, and any material which passes by the knife and then falls from the cylinder may deposit on the inner edge of the knife blade on the side toward the cylinder and will eventually build up a deposit of such thickness as to prevent the convenient adjustment of the knife and, in some cases, as to press with considerable force against the drum opposite the base of the knife. It has been found that this objection may be entirely avoided by fastening a guard plate 20 on the inner side of the knife blade extending over the base in which the knife blade is carried, and by extending a conduit 21 for the full length of these knives, the conduit being provided with openings, which will direct vapor sprayed therethrough toward the bases of the knives in such a way as to prevent the formation of any deposits between the knives and adjacent parts, and the cylinder. The material which may be sent through the pipe 21 may be either steam, water or the liquid contained in the reservoir in the cylinder 1, and in any event will serve to wash off any material which is deposited on these parts, and to return the same to the liquid reservoir in the base of the chamber.

It frequently happens that a deposit forms on the end of the cylinder and this must be either prevented or removed. The formation of such deposit may be entirely prevented by directing a jet of steam or other vapor or liquid against the edge or end of the cylinder, as indicated in Fig. 2, a conduit 23 having its end turned so as to spray a jet of liquid or vapor at an acute angle against the end 24 of the drum 4 and downwardly, so as to wash any material depositing thereon into the reservoir in the chamber.

The action of the present apparatus is as follows:—After the liquid has been intro-

duced into the vacuum chamber and the tank 3, the pump 15 is started to set up a suction through the apparatus and create a high vacuum in the vacuum chamber 1. The drum 4 is rotated and as the drum dips into the liquid in the tank 3 a thin film of the solution to be evaporated is spread over the surface of the heated drum 4 and the dried product is scraped therefrom by means of the knives 5. The vapors from the liquid are carried through the conduit 10 and some of the solid material is inevitably carried along with these vapors. The vapor curtain or screen, which is sprayed from the openings 18 in the conduit 17 transversely of the enclosing conduit 10, causes the particles of solid matter to be deposited upon the walls of the conduit 10, from which they drain back into the drying chamber and into the liquid in the bottom thereof. The apparatus may of course operate on different kinds of material, but it has been very successfully used in connection with the drying of lime sulphur solutions.

25 By the methods and apparatus described we have succeeded in avoiding loss of material in the exhaust vapors, and what is more important, have effected a great saving in time by preventing formation of objectionable deposits at various points which could only be removed when the apparatus was stopped and opened to workmen, which was in many cases unpleasant and sometimes extremely detrimental to their health on account of the gases arising from the material undergoing drying.

Other modes of applying the principle of our invention may be employed instead of

the one explained, change being made as regards the steps or mechanism herein disclosed, provided the means stated by any of the following claims or the equivalent of such stated means be employed.

We therefore particularly point out and distinctly claim as our invention:—

1. In a method of the character described, the steps comprising evaporating a fluid in a vacuum chamber and then removing suspended material from the evolved vapor by subjecting it to the entraining action of a transversely directed vapor screen.

2. In a method of the character described, the steps comprising evaporating a fluid, then passing the evolved vapor through a constricted passage and removing suspended material from such vapor by subjecting it in said passage to the entraining action of a transversely directed vapor screen.

3. In a method of the character described, the steps comprising removing suspended material from evolved vapor by subjecting such vapor to the entraining action of a transversely directed vapor screen and then collecting the entrained material.

4. In apparatus of the character described, the combination of a vacuum drying chamber, a suction conduit leading therefrom, a perforated pipe extending longitudinally of said conduit, and connections adapted to supply steam to said pipe so as to provide a curtain of water vapor in said conduit through which the vapors being evacuated from said chamber have to pass.

Signed by us, this 9th day of April, 1918.
MARTIN J. O'BOYLE.
EDWARD C. HOLTON.
